United States Patent Office

Des. 217,272
Patented Apr. 21, 1970

217,272

TOY ENGINE

Robert Genin, Scarsdale, N.Y., assignor to Child Guidance
Toys Inc., Bronx, N.Y., a corporation of New York

Filed May 23, 1969, Ser. No. 17,302

Term of patent 14 years

Int. Cl. D21—02

U.S. Cl. D34—15

Fig. 2.

Fig. 3.

FIG. 1 is a perspective view of a toy engine showing my new design. The operating pistons and gears are visible through the transparent cylinder block;

FIG. 2 is an elevational view of my design as seen from the right side thereof;

FIG. 3 is a top plan view of my design;

FIG. 4 is a front elevational view of my design; and
FIG. 5 is a rear elevational view of my design.

I claim:

The ornamental design for a toy engine, as shown and described.
